O. Marland.
Paper Mach.

No 12,442. Patented Feb. 27, 1855.

UNITED STATES PATENT OFFICE.

OBADIAH MARLAND, OF BOSTON, MASSACHUSETTS.

ROLL AND DRIER FOR PAPER-MAKING.

Specification of Letters Patent No. 12,442, dated February 27, 1855.

To all whom it may concern:

Be it known that I, OBADIAH MARLAND, of Boston, in the county of Suffolk and State of Massachusetts, have invented certain new 5 and useful Improvements in the Rolls and Driers of Paper-Machines, of which the following is a full, clear, and exact description, reference being had to the annexed drawing, making a part of this specification.

10 The rolls and driers of paper machines require certain characteristics which it has heretofore not been found practicable to attain for them to the degree of perfection which is desirable; while the methods by 15 which it is sought to attain these ends, and the great time and care bestowed upon the manufacture of the rolls and driers, render them exceedingly expensive. Some of the rolls work constantly in the paper pulp or 20 water, and must therefore be of a material not easily corroded thereby, nor by the agents which the pulp or water may contain. All of the rolls, but some more than others, require a perfectly flawless metallic surface, 25 particularly in machines for making the finer kinds of paper, while it is necessary that some of them, as the press rolls, be of a strength that shall enable them to endure the great pressure to which they are subjected. 30 Various materials have been used, and different methods of construction employed; all of them, however, have been liable to some objection. Where iron is used the requisite stiffness and strength is attained, but the cast metal, being filled with 35 flaws, produces but an indifferent surface even after the apparent defects have been plugged with great care. For such rolls and driers as are exposed to moisture and are 40 worked in contact with the moist paper or felt, iron is very objectionable, owing to its extreme liability to rust, which not only soon destroys the surface of the roll itself, but speedily destroys the felt which comes in 45 contact with it. For such rolls a surface of copper, bronze, or other similar metallic alloy, is preferred, and they are usually constructed either by casting or by shrinking hollow cylinders of malleable copper on to 50 iron foundations. When the method of casting is adopted, the requisite strength is easily given to the press rolls, but, as in the case of the cast iron, such rolls are always more or less unsatisfactory. The casting is never 55 perfect, and the flaws require to be bored out and their places filled with plugs. This

repairing and plugging, besides being very expensive, produces a surface of very variable density, which materially diminishes the value of the roll, and gives a less perfect 60 surface to the paper than is produced by a pure deposited metal. In addition to these more apparent flaws, the surface of the cast metal is filled with minute imperfections, too small and too numerous to be remedied by 65 plugging, but of sufficient magnitude to leave their impress upon the paper and detract from the finish of its surface. For such rolls as require perfection of surface in 70 union with strength, as in the case of the press rolls, hollow cylinders of copper have been shrunk on to accurately turned iron rolls, but it was found that after being used for a short time, the copper was rolled out and elongated, there being no union between 75 the two metals to prevent them from separating, and the plan was abandoned.

After various experiments I have discovered that all the above objections may be removed, and a perfectly faultless surface 80 produced, by the use of metal deposited by means of voltaic or electric action, a metallic cylinder, of any required strength, being used to receive the deposit. The surface thus produced is without blemish and un- 85 equaled by any surface heretofore produced, the deposited metal being peculiarly adapted to give a superior finish to the surface of the paper, and to resist the action of the water and the agents which it may contain, 90 while the cost of such roll or drier is greatly less than that of the copper or composition rolls and driers now in use.

To enable others skilled in the art, to make and use my invention I will proceed 95 to describe the manner in which I have carried it out.

A metallic roll is prepared, of dimensions slightly less than those required for the finished roll, and of a strength proportioned to 100 the character of the work it has to perform. The surface of the roll is cleansed, in the usual manner, to secure the adhesion of the deposited metal. Those parts not intended to receive the coating are covered with wax, 105 gutta percha, or any other suitable non-conducting substance. The roll is then immersed in a solution of the metal to be deposited, and the usual connections made with a galvanic battery, or a magneto-electric 110 machine, in the manner well known to all workers in electro-metallurgy, and the depo-

sition continued until the required thickness of metal is attained. About three-sixteenths of an inch I have found to answer every purpose.

5 The accompanying drawing is a view of a paper-machine-press-roll, the dotted line, at α , showing the thickness of the copper coating.

Heretofore I have spoken of copper as the 10 material used for covering the rolls and driers, but I do not confine myself to the use of this metal, as zinc, and perhaps other metals, may be employed; and I do not claim the use of any particular metal for the purpose. 15 Neither do I claim the covering of

one metal with another by means of galvanic or electric deposition, but—

What I do claim as my invention, and desire to secure by Letters Patent, is—

The method herein described of making 20 paper machine rolls and driers; a metallic foundation of the requisite strength and thickness being made use of for the body of the roll, upon which a surface of copper, or other suitable metal, is deposited by galvanic 25 or electric action, for the purpose set forth.

OBADIAH MARLAND.
